OVER-ALL SNAP LOCK PROTECTOR FOR
FUEL TANK CAPS

Assad M. Malluk, New York, N. Y.

Application August 11, 1936, Serial No. 95,314

5 Claims. (Cl. 70—164)

The present invention relates to a snap lock for application to the filling necks of tanks for fluids, particularly, but not restricted to, the filling necks of automobile fuel tanks. A number of different forms of filling neck locking caps have been proposed including a cap per se carried by a cover member so designed that when the cap element is latched to the neck, as by spring dogs placed through openings in the neck flange and held when the cap is rotated a slight distance, it can be unlocked from the cap and freely rotated so that it is impossible to move the cap until a key is inserted and the cover member and cap locked together. Thereupon rotation of the cover member will carry with it the cap element and the two elements thus held firmly together can be removed from the filling neck.

The object of the present invention is to provide an over-all snap lock adaptable for the freely removable filler neck caps in universal use, so that the device can be applied to any filling neck closed by a cap.

A further object of the invention is to provide a simple, inexpensive and strong over-all snap lock for filling the necks of fluid containing tanks which is applied, when unlocked and in place over the filler neck opening, by moving a lateral wall of the device into snap engagement with a latch, the latch being key-operated for releasing the device.

Further objects of the invention will herein-after appear.

The invention will be described with reference to the accompanying drawings, in which—

35 Figure 1 is a perspective view of an embodiment of the invention applied to the top of a fuel tank, a fragment of the latter being shown.

Figure 2 is a bottom plan view of the device, partly broken away.

40 Figure 3 is a sectional elevation on the line 3—3, Figure 2.

Figure 4 is a fragmentary and enlarged section on the line 4—4, Figure 2.

Figure 5 is a detailed perspective view of the latch member.

Figure 6 is a perspective view of a modified form of the structure.

Figure 7 is a perspective view of a further modification of the structure.

50 Figure 8 is a plan view of the two elements shown in Figure 7, separated and partly broken away.

Referring to the drawings, I have indicated in Figures 1 and 7, a fragment of the upper portion of a liquid containing tank indicated at 1

and having the annular vertically extending filling neck 2 to which has been applied a closure cap 3 of customary form. In practice, this cap is frictionally held on the neck 2 although in some cases it may be threaded thereon.

In the embodiment of the invention illustrated in Figures 1 to 4 inclusive, the overall snap lock protector comprises an annular top member 4 with which is cast a vertically extending neck 5 apertured to receive the rotary lock member 6 adapted to receive a key as indicated at 7, Figure 1.

The rotary lock member 6 carries a depending stud 6x which enters a cam aperture 8x in a sliding latch member 8. The latch member is held against the inner wall of annular top member 4 by means of a three-legged spring plate 9 secured in position by means of the screws 10.

A recess may be formed in member 4 as indicated by the dotted lines at 11, Figure 2, and the full lines 11, Figure 3, for the rear end of sliding latch member 8. The sliding latch member carries an upwardly projected stud 12 engaged by a spring 13 having one end fixed to a pin 14 (Figure 2) secured to top member 4 by means of which the latching slide member is normally held in outward projected position. At its outer end the latching slide carries a latch hook 8xx.

Depending from top member 4 is a half-round vertical side member 15 and hinged to the side member is the movable half-round side member 16. Each of the side members 15, 16, is formed with an inwardly projected horizontal flange f so as to normally lie under the cap 3. In the present instance, the hinge is formed by a plurality of spaced lips a carried by each of the side members 15, 16, so spaced that the lips of one member lie within the spaces provided between the lips of the other member, the lips being apertured to receive the hinge pin 17 which is tightly fitted within an aperture formed in member 4 as more particularly shown in Figure 3.

Movable side member 16 is formed with an inwardly projected shoulder 16x adapted to be engaged by the latch hook of sliding latch member 8.

The device is applied to the filling neck cap of the liquid containing tank by moving the top member with its depending side member 15 laterally until the half-round flange of member 15 lies under the cap 3, whereupon member 16 may be moved inwardly to bring its flange under the cap member and cause its shoulder 16x to be brought in such position that it may be

snapped over the springy latch hook end of member 8.

When key 7 is turned the pin 6x which is positioned eccentrically of member 6 will act upon the cam slot 8x to retract the latching slide, and movable wall member 16 may be swung to the position shown in Figure 1, thus releasing the device. The free end of movable wall 16 may carry a stud 18 to enter socket 19 (Figure 4), if desired.

In the structure of Figure 6, the latching slide of the member which it engages and also the hinge construction and the half-round side wall construction is the same as that in the preceding figures and the same numerals are indicated for these parts. The difference in construction is that side wall 16 carries part of the top wall as indicated at 20, the side wall 15 carrying the remaining part of the top wall shown at 21, and the inner margin of top wall member 20 is reduced in height to form a shallow lip 20x merging with a shallow lip 22 carried by side wall 16, the latter lip fitting under side wall 15 and lip 20 fitting under top wall 21 so as to form a water-tight connection at these points.

In the structure of Figures 7 and 8, the device comprises two halves, each having a half-round top wall 23, 23x, and depending side walls 24, 24x. Side wall 24x carries at one end a hook 25 adapted to enter a hooked-shaped aperture at 26 in side wall 24. The end of side wall 24 opposite hook 25 with a latching boss 27 having a shoulder latch recess at 28 adapted to receive latch hook 29 carried by a key-operated barrel 30, Figure 7, the barrel having a key slot at 31 by which the barrel can be rotated so that when the two halves are placed together over upon a closure cap such as 3, Figure 1, the cap cannot be rotated, inasmuch as the protector will cover the same and its free rotation will prevent low friction rotation of the cap.

If desired, either one of the embodiments illustrated in the drawings will carry ball bearings for light frictionless engagement with side wall of the cap 3, and in Figures 1 to 3 inclusive, I have shown the side walls 15, 16, formed with inwardly projecting bosses 32 carrying ball bearings 33.

Having described my invention, what I claim and desire to secure by Letters Patent, is as follows:

1. An over-all protector for the filling necks of tanks for fluids, comprising a closure member having a top wall and an upwardly projected neck, an integral vertical semi-annular side wall and an inwardly projected flange carried by said side wall at its base, a rotatable key actuated barrel in said neck of the closure member, a latch slide operatively connected to the barrel at the underface of said top wall, and a second closure member having a hinge connection with the first member, said second closure member comprising a semi-annular vertical wall carrying an inwardly projected flange at its base, said side wall having a latch receiving element adapted to be engaged by said latch slide.

2. An over-all protector for the filling necks of tanks for fluids, comprising a closure member having a top wall formed with an upwardly projected neck, a key-operated rotatable barrel carried within said neck of the closure member, a

side wall, an inwardly projected flange carried by said side wall, a latch slide formed with a cam aperture, a stud carried by the barrel and entering said aperture, a prong retaining spring secured to the underface of the top wall and supporting the slide, a second closure member hinged to the first member, said second closure member formed as a ring section with an inwardly projected horizontal flange at its base, the ring section having a latch receiving element adapted to be engaged by said latch slide, the ring element being movable to a position under the top wall of the first-named closure member.

3. An over-all protector for the filling necks of tanks for fluids, comprising a closure member having a top wall formed as an annular plate, formed with an axial upwardly projected neck and a semi-annular depending side wall carrying an inwardly projected flange at its base, a key-operated rotatable barrel in said neck of the closure member, a latch slide at the base of the cap and having a cam opening, a stud carried by the barrel and entering said cam opening, a spring engaging the latch slide for imparting endwise movement thereto, a latch hook carried at one end of the slide, and a second closure member formed as a ring section having a latch receiving element adapted to be engaged by said latch hook, and interengaging connecting means carried by the closure members opposite said latch hook.

4. An over-all protector for the filling openings of tanks for fluids, comprising a closure member having a top wall, an integral vertical semi-annular side wall and an inwardly projecting flange carried by said side wall, a latch carried by said closure member and normally projected near one edge of the semi-annular vertical wall, the second closure member movable relatively to the first member, said second closure member having a semi-annular vertical side wall carrying an inwardly projected flange, its side wall having a latch receiving element adapted to be engaged by said latch, means for operating said latch, inter-engaging connecting means carried by the closure members opposite said latch receiving element, and anti-friction members carried by the vertical side walls of the two closure members.

5. An over-all protector for the filling necks of tanks for fluids, comprising a primary closure member having a vertical semi-annular side wall and an inwardly projected flange carried by said side wall, a latch member carried by said closure member, a second closure member movable relatively to the first member, said second closure member having a semi-annular vertical side wall complementary to the first named side wall to complete an annulus, a latch receiving element adapted to be engaged by said latch, a top wall carried by the primary closure member and serving as the cover of the protector and having a semi-annular inset abutment for the side wall of the second closure member, which adapts said top wall as an overlying water seal member for the said second closure member, means for operating said latch, and inter-engaging connecting means carried by the closure members.
